UNITED STATES PATENT OFFICE.

DAVID E. OLDS, OF NEWARK, NEW JERSEY.

METAL TIE AND RAIL FASTENER.

No 823,629.

Specification of Letters Patent.

Patented June 19, 1906.

Application filed June 29, 1905. Serial No. 267,487.

To all whom it may concern:

Be it known that I, DAVID E. OLDS, a citizen of the United States, residing at Newark, in the county of Essex and State of New Jersey, have invented certain new and useful Improvements in Metal Tie and Rail Fasteners; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to that class of rail-supporting means for railways in which wood and iron or steel are employed together, the former to secure the desired elasticity in the foundation or base for the rails, so that the cars are cushioned in their movements thereover, and the latter to secure the increased durability such as steel and iron afford.

The objects of the present improvements are to reduce the cost of construction, to reduce the cost of maintenance, to enable the wear to be taken up with greater convenience and ease, and to secure other advantages and results, some of which may be referred to hereinafter in connection with the description of the working parts.

The invention consists in the improved supporting-bed for railway-rails and in the arrangements and combinations of parts of the same, all substantially as will be herein-after set forth, and finally embraced in the clauses of the claim.

Referring to the accompanying drawings, in which like numerals of reference indicate corresponding parts in each of the several figures, Figure 1 is a plan showing a portion of one of my improved beds or foundations and connections by which a rail is fastened. Fig. 2 is a section of the same, taken at line x of Fig. 3. Fig. 3 is a side elevation of the same. Fig. 4 is a detail plan of one of my improved metal ties, and Fig. 5 is a section of the same taken at line y.

In said drawings, 10 indicates a railway-rail having the usual head 11, web 12, and base-flange 13.

14 is a suitable metallic chair or tie-plate upon which the rail is secured.

15 indicates a wooden base-block upon which the tie-plate or chair 13 is seated, but 55 upon which the rail 10 may be directly seated,

if preferred. While I prefer wood in the construction of the base-block 15, I may use other more or less elastic material, such as compressed pulp or similar material, adapted to reduce vibration and provide a smooth and easy movement of the train over the rails. The block 15 is comparatively short and inexpensive as compared with wooden ties now commonly in use. Said block is in turn seated upon a metallic tie 16. (Shown in detail in Figs. 4 and 5.) Said metallic ties are provided at their opposite longitudinal edges with depending flanges 17 to give to the said tie adequate rigidity and strength, though the said tie may be made of channel-iron in any desirable form of cross-section. Near the ends of the said tie near where the same are crossed by the rails are formed bosses or pintles 18 for holding the blocks 15 in place, preferably formed integral with the tie 16 by forcing out the metal of the said tie by means of punches or other formers, the said pintles 18 serving as means for holding the said opposite ends of the rail-supporting base-blocks 15 in place. Certain of the pintles 18 extend upwardly to receive the said block 15 between. Other of said pintles extend downwardly, as at 181, to receive a second similarly elastic block 19, lying underneath the metal tie between the flange 17 thereof. Between the inner series 191 191 of pintles near the opposite ends of the tie the said tie is raised, as at 20, to throw the water away from the top of the said tie and toward the opposite ends where the tie is perforated, as at 192, to permit a free-drainage.

Underneath the bottom block 19 is preferably arranged a metallic plate 21, having at opposite ends integral extensions 22, adapted to enter the small angles of a rail clamping or fastening frame 30, hereinafter described. Said extensions 22 project beyond the opposite sides of the tie and enter into separable relation with the angular parts of the fastener 30.

The fastener 30, preferred for the purposes of this case, is illustrated in Figs. 1 and 3 more fully, and consists of an iron or steel rod or bar bent into frame-like structure, and thus adapted to engage the flanges of the rail and, in connection with the key-plate 21, hold said rail firmly in place on the tie and its blocks. Said frame-like bar is bent, as at 31, to engage the top of the flange 13 at one side of the rail and hold said flange down upon its seat on the plate 14. From this said flange 13 the

frame-like fastener extends at an inclination downward at opposite sides of the block 15 and tie 16, as at 32, to points directly beneath the web of the rail and below the horizontal plane of the bottom of the lower block 19, where the extensions of the fastener 30 are bent or turned upward and form angles 221 to receive the key 22.

From the angles 221 the bent rod or bar extends upward at 33 at an inclination opposite that of the inclined extension 32 to a point above the opposite rail-flange 13, where the ends of the frame-like fastener are threaded, as at 34, to receive nuts 25. On said upwardly-extending ends are arranged the keeper 26, which is perforated to permit the passage of said ends upward therethrough and extends horizontally from said ends toward the rail, said keeper projecting over the flange of the rail, as shown in Fig. 3. By arranging the frame-like fastener in connection with the rail, blocks, tie, and keeper in the manner illustrated in the drawings and inserting the key-plate 21 beneath the bottom block, and within the angles of the fastener and then screwing down the nuts 25 against the keeper 26 the parts are securely clamped together; but the peculiar relation of the wooden blocks to the metal parts is such as to avoid unpleasant vibrations and render the road-bed easy and smooth, as will be understood.

Having thus described the invention, what I claim as new is—

1. The combination with a metallic tie and the railway-rail, of elastic blocks arranged above and below said metallic tie, and fasteners holding said rails, blocks, and metallic tie in fixed relation, substantially as set forth.

2. The combination with a metallic tie and the flanged railway-rails, of elastic blocks and fasteners extending from the top of the flange of said rail downward at the sides of the block and tie and having a plate extend-

ing underneath the tie, substantially as set forth.

3. The combination with a metallic tie and a flanged railway-rail, of a block of wood seated on said tie, a plate seated on said block and adapted to receive said rail and a frame-like fastener extending from one flange of the rail downward at opposite sides of the block and tie and underneath said tie to a plate extending underneath the tie, and thence extending upward, a keeper-plate receiving the upper ends of said fastener, nuts and said plate extending underneath the tie, substantially as set forth.

4. In a rail-fastening, the metallic tie having integral lugs extending upward from the top of the tie, in combination with elastic blocks inserted between said integral lugs and prevented from moving lengthwise of said metallic tie in either direction, and clamping means extending underneath the said block and tie and upward to engage the opposite sides of the base-flange of the rail.

5. The combination with the metallic tie having upwardly and downwardly extending lugs, of elastic blocks arranged above and beneath the metallic tie and means for fastening the upper and lower blocks to the tie and the rail onto the upper block, substantially as set forth.

6. The combination with the metallic tie, of wooden blocks arranged above and beneath the tie, the upper block furnishing a seat for the rail, and means for clamping the upper and lower blocks to the tie and the rail on said upper block, substantially as set forth.

In testimony that I claim the foregoing I have hereunto set my hand this 7th day of June, 1905.

DAVID E. OLDS.
